Primary Examiner — Robert M. Spear*Assistant Examiner* — Ryan Harvey(74) *Attorney, Agent, or Firm* — Taft Stettinius & Hollister LLP(57) **CLAIM**

The ornamental design for a collapsible exercise frame, as shown and described.

DESCRIPTION

FIG. 1 is a front, right perspective view of a collapsible exercise frame showing my new design;
 FIG. 2 is a front perspective view thereof;
 FIG. 3 is a side perspective view thereof;
 FIG. 4 is a top plan view thereof; and,
 FIG. 5 is a bottom plan view thereof.
 The broken lines form no part of the claimed design.

1 Claim, 5 Drawing Sheets(56)
